UNITED STATES PATENT OFFICE.

PAUL F. COX, OF CHICAGO, ILLINOIS.

PRINTING PRESS.

Application filed April 16, 1921. Serial No. 461,905.

To all whom it may concern:

Be it known that I, PAUL F. Cox, a citizen of the United States, residing at Chicago, in the county of Cook and State of Illinois, 5 have invented certain new and useful Improvements in Printing Presses; and I hereby declare that the following is a full, clear, and exact description thereof, reference being had to the accompanying drawings, 10 which form part of this specification.

This invention is an improvement in flat bed web perfecting printing presses in which the impression cylinders are reciprocated over beds carrying flat forms of type or 15 flat printing surfaces.

The objects of the present invention are to increase the capacity of such press so that for each stroke of the impression cylinders a plurality of papers will be printed 20 on the web; to provide ample time for shifting the web while the impression cylinders are off impression at the ends of the bed so that the web can be shifted without rupturing it when the press is operated at 25 high speed; to provide improved means whereby the web may be continuously fed into the press and continuously delivered therefrom, and the portion of the web intermediate the feed and delivery be intermittently shifted forward through the press; 30 to provide novel means for slackening the intermediate portion of the web between the feed and delivery while the web is being shifted over the beds by the looping devices, 35 and for properly tensioning this intermediate portion of the web just prior to and during the printing operation; to provide novel means for inking the forms on the press on both the forward and backward strokes of the 40 cylinders and intermediate the successive impressions by the cylinders in each pair so that the forms will be inked on both the backward and forward strokes of the cylinders and also inked intermediate the 45 impressions produced by the adjacent or twin impression cylinders which operate on each bed.

In the accompanying drawings I have 50 illustrated one practical printing press embodying the invention and will explain the invention with reference thereto, and then set forth in the claims the essentials of the invention and the novel features of construction and novel combinations of parts 55 for all of which protection is desired.

In said drawings;

Fig. 1 is a side elevation of the complete press.

Fig. 2 is a longitudinal vertical section 60 thereof.

As shown in the drawings the press has two beds 1 and 1^a arranged parallel and preferably one above the other, and mounted in suitable side frames to support the same. Cooperating with the bed 1 is a pair 65 of impression cylinders 2, 2^x, and cooperating with the bed 1^a is a pair of impression cylinders 2^a, 2^{ax}. These cylinders are all mounted or journaled in suitable bearings in cross heads 3 which cross heads are mounted 70 to slide in guides in the side frames of the press in the well known manner. These cross heads may be reciprocated longitudinally of the press by any suitable means so as to move the pairs of cylinders back and 75 forth over their respective beds. I preferably employ pitmans 3^a connected to crank gear wheels 4 mounted on a shaft 4^a journaled in the side frames of the press.

The web W to be printed is led from a 80 roll W to and over an infeed roll 5, which may be provided with coacting tapes 5^a. The web is then led over a looping roller 6^a, mounted in one end of rocking levers 6. The web then passes over a guide roller 3^e mounted 85 on the cross heads 3 below the upper bed 1; then under the cylinder 2^a up over roller 7^a movably mounted on the cross heads, as hereinafter referred to, above and between the cylinders 2^a, and 2^{ax}; then down under cylinder 2^{ax} and up over a roller 3^y 90 mounted on the cross head; then out between beds 1 and 1^a to and over a guide roller 10^a, mounted on the end of the press frame 10; then up over a guide roller 10^b 95 mounted on the end of the frame then back to and over a guide roller 3^e mounted on the cross heads above the upper bed 1; then down under the cylinder 2^x; then up over a guide roller 3^f mounted on the cross heads; 100 then down under the cylinder 2^x; then up over a guide roller 3^g mounted on the cross heads; then to and over a looping roller 6^b mounted on the other end of the levers 6; and then to a delivery or outfeed roll 8 mounted on 105 the frame of the press; and which may be provided with a set of co-acting tapes 8^b to assist in delivering the web to the folder (not shown).

It will be seen (see Fig. 2) that the web 110

is first properly led to each cylinder 2^a, 2^{ax} to be presented thereby to the forms on the bed 1^a; and is then led to the cylinders 2^x and 2 to be presented thereby to the forms 5 on the bed 1.

The levers 6 are journaled on studs or shaft 6^c mounted on the side frame 10 of the press, and these levers may be oscillated by means of a link 6^d one end of which is 10 pivoted to a lever 6 and its other end to the longer arm 6^e of a bell-crank lever pivoted at 6^f on the frame 10 and the shorter arm 6^g of this lever carries a roller engaging a cam 9 mounted on a stud or shaft 9^a supported 15 on the main frame. In the example shown the roller on arm 6^e is held in contact with the periphery of cam 9 by means of a spring 6^h as indicated in the drawings, this spring operating the lever 6 during the taking of 20 impressions on the web. Any suitable cam may be used in place of cam 9 for the purpose described.

The crank gears 4 mesh with gears 5^b on the infeed roll 5 (Fig 1) and directly drive 25 the latter at the proper speed. The outfeed roll 8 is similarly driven by a gear 8^a directly meshing with the crank gear 4.

The cam shaft 9^a is driven by a gear 9^b meshing with a gear 4^a on the shaft 4^a. The 30 crank gears may be driven by pinions 11^a on a drive shaft 11 journaled in the frame, pinions 11^a meshing with the gears 4 as shown. The shaft 11 may be driven directly or indirectly by a motor of any suitable kind 35 (not shown).

In the press shown, the two cylinders operate on each bed on each stroke of the cross heads, and two impressions will be made thereby on the web on each stroke; and 40 therefore it is necessary to provide suitable mechanism for inking the forms between the successive operations made by the cylinders in each pair.

In the example shown I provide between 45 the cylinders 2 and 2^x an inking roller 12^a which is carried in suitable guides attached to the cross heads, and this roller 12^a performs the function of both distributor and form roller and will be hereinafter explained. Between the cylinders 2^a and 2^{ax} I provide a similar roller 12^{ax} which is also carried by the cross heads like the roller 12^a. I preferably also provide a distributing roller 12^b coacting with the roller 12^a, and a 55 like distributing roller 12^{bx} coacting with the roller 12^{ax}.

At each side of the bed 1 I provide ink distributing plates 13 and 13^a and at each side of the bed 1^a I provide similar ink distributing plates 13^x and 13^{ax}. The ink is supplied to the plate 13^a from a fountain 14 mounted on the main frame 10 adjacent the outer end of the plate 13^a. Ink is taken from the fountain 14 by a ductor roller 15 carried on the cross heads; and ink is transferred

from the roller 15 through a series of distributing rollers 15^a carried on the cross heads to a form roller 15^b adjacent the cylinder 2^x. The rollers 12^a and 15^b act as distributing rollers on the plates 13^a and also as 70 transfer rollers for transferring ink from the table 13^x to the table 13. A form roller and distributor 15^c is provided on the cross heads adjacent the cylinder 2^a; and a like roller 15^{cx} adjacent the cylinder 2^{ax}. The 75 rollers 15^c and 12^a act as distributing rollers on plate 13, and also as form rollers.

The inking plate 13^{ax} is suitably provided with ink from a fountain 14^a mounted on the end of the press, from which fountain 80 the ink is taken by a ductor roller 15^x mounted on the cross heads, and transferred from the ductor rollers 15^x through distributing rollers 15^{ax} to a form roller 15^{bx}. Ink is transferred from plate 13^{ax} to plate 13^x by 85 roller 12^{ax}.

I am able to dispense with two fountains by using the ink plates at opposite ends of each bed. The surfaces of the plates are set slightly below the type surface so that the 90 web around the lower periphery of the cylinder will not contact with the ink plates as the cylinders pass over the plates and during the intermediate shifting of the web. The ink is supplied from the fountains to 95 the ductor rolls once for each reciprocation of the cross heads and is well distributed before being delivered to the forms. The form rollers not only supply ink to the forms but also travel onto the inking plates and 100 serve to supply ink thereto and distribute ink thereon. The form rollers 12^a and 12^{ax} also serve as form rollers to spread the ink over the form both ways of travel and in addition spread ink over the nearest half of 105 both ink plates and thus supply the ink for the form rollers 15^c and 15^{cx} and for the distributing rollers above them.

In order to slack the web between the feed and delivery devices during the time the 110 intermediate part of the web is being drawn forward over the beds by the action of the looping rollers, and the delivery—and to ease the friction of the web against the impression cylinders while they are out of impression and to restore the desired uniform tension of the web before and while the web is being actually printed upon, the guide roller 7^d is shown as mounted on arms or levers 7^a (one of which is pivoted as at 7^b on 115 each cross head). One lever 7^a carries a roller 7^c adapted to engage a cam bar 7^x attached to the underside of the bed 1 or other convenient part of the machine frame. The ends of this bar 7^x are tapered as shown so 120 that the roller 7^c may easily engage and disengage said cam bar during the reciprocation of the cross heads. Just before the cylinders impinge the web against the type form the roller 7^c will engage one end of the 125 130

cam bar and rock the lever 7^a so as to slightly raise the roller 7^a just before the impression and thus properly tension the web before and during the time the web is being printed.

5 When the cylinders clear the form after an impression, the roller 7^a clears the opposite end of the cam bar and thus permits the roller 7^a to slightly drop and slack the web between the infeed and the delivery rollers.

10 A very slight movement of the roller 7^a would suffice to properly slack and tension the web; a movement of about $\frac{1}{2}$ of an inch of the roller 7^a would suffice for this purpose.

15 *Operation.*

By using two impression cylinders for each bed I obtain double the number of impressions upon the web from and upon the same form and upon each and both strokes of the cross heads. The length of travel of the cylinders of course is somewhat increased; as compared with a single cylinder press— (say 48 inches instead of 38 inches as in the 25 single cylinder press). This would allow 32 inches of travel during the impression, or while the paper is nipped between the cylinders and form, and during that time the feed rollers feed 20 inches of web which is taken up by the looping roller 6^a and the delivery roller 8 delivers a like amount of web, which is supplied by the looping roller 6^b operated by the cam 9 in proper time. The feed roll 5 feeds 24 inches of web while the 35 cylinders are clear of the type forms at each end of the bed, and this 24 inches of web together with the 20 inches of web taken up and supplied by the looping rollers during the taking of impression makes 40 a total of 44 inches of web fed for each stroke of the cylinder, and this 44 inches of web is shifted between the looping rollers 6^a, 6^b and between the beds and cylinders during the time that the cylinders are out 45 of contact with the forms at each end of the beds. This shifting movement of 44 inches of web is effected by the combined action of the delivery roll 8 and upper looping roller 6^b. The feed and delivery rolls operate continuously, and the intermediate portion of the web is alternately held stationary during the taking of impression by the action of the looping roller 6^a during which time the amount of the web required by the 50 continuously operating delivery roll 8 is supplied from the looping roll 6^b; 88 inches of web is fed into and delivered from the press with each revolution of the crank wheels—or complete reciprocation of the cross heads. 55 This enables me to produce twice as many perfected papers for each reciprocation of the cross heads as is produced by the old style single cylinder cross heads. By the increased rotary action in the intermittent 60 movement of the web 24 inches of web is

transferred while the press is off impression by the action of the delivery roll 8; and 20 inches of web is transferred from the looping roller 6^a to the looping roller 6^b by the action of the looping roller 6^b while the 70 cross head or cylinder is traveling 48 inches and back (total 96 inches). This enables me to print 88 inches of web including margins for each reciprocation of the cylinder which is almost equal to a rotary press product and I thus gain one complete perfected paper with an increase of only 10 inches of travel. In other words where one paper would require 38 inches of travel, by increasing the travel 10 inches (48 inches) I 80 gain an additional paper.

The infeed and outfeed devices are properly rotated in the right direction and proper time by being geared directly to the main drive crank wheels, which for example are 56 inches on pitch line. The gears on the infeed and outfeed rolls are 14 inches, and such in and out feed rollers are 7 inches in diameter. Thus for each revolution of the main crank wheels or reciprocation of 85 the cylinders 88 inches of web is fed through the press from the feed to the delivery, equaling four 22 inch severed sheets.

In this construction I have eliminated a 90 large number of gears, shafts and studs heretofore used in flat bed web presses. I have also eliminated two ink fountains; and such fountains are at the end of the press where they are readily accessible and can be 95 filled and set while the press is in operation.

100 What I claim is:

1. In a flat bed web printing press the combination—a bed adapted to carry a 105 printing surface;—a pair of cylinders co-operating with said bed; means for reciprocating the cylinders over the bed; web feeding and delivering mechanism; means for directing the web from the feeding mechanism successively between the cylinders and bed to the delivery; means for looping the web between the cylinders so that two impressions are made on the web from the same form by the cylinders on each 110 stroke such impression being on different portions of the same web; means for stopping the forward movement of the portion of the web being printed just prior to and during the printing operation; and means for shifting forward the printed portion of 115 the web a distance equal in length to two impressions on the web plus margins while the cylinders are clear of the forms at each end of the bed.

2. In a printing press as set forth in claim 125 1, means at each side of the cylinders for inking the forms on the bed and means between the adjacent impression cylinders for inking the forms.

3. In a printing press as set forth in 130

claim 1, means for tensioning the intermediate portion between the feed and delivery just before and during the printing operation, and for slackening such intermediate portion of the web after the printing operation and while such portion of the web is being shifted forward.

4. In a printing press as set forth in claim 1; a looping roller traveling with the cylinders; rocking levers carrying said roller, a cam adapted to engage the lever and move the roller so as to tension the intermediate portion of the web during the printing operation, the cam permitting the roller to move and slack this portion of the web after the printing operation.

5. In a flat bed web printing press as set forth in claim 1; an inking plate at each end of the bed and form rollers at both sides of 20 and intermediate the cylinders adapted to cooperate with the said plates and ink the forms, substantially as described.

6. In a flat bed web printing press, a pair of beds adapted to carry printing forms or surfaces; a pair of cylinders cooperating with one bed, a second pair of cylinders cooperating with the other bed; means for reciprocating said cylinders; web feeding and delivering mechanism; means for directing the web from the feeding mechanism successively between the pairs of cylinders and beds to be printed, so that two impressions are made by each pair of cylinders from the form on the related bed at 35 each stroke of the cylinders; means for looping the web between the cylinders in each pair so that the two impressions produced by such cylinder from the form on the related bed will be on different portions of the same web; means for stopping the forward movement of the portions of the web being printed just prior to and during the printing operation; and means for shifting forward the printed portions of the web a distance equal in length to two impressions on 40 the web plus margins while the cylinders are clear of the forms at each end of the bed.

7. In a flat bed web printing press, having a pair of beds, cylinders cooperating with 50 said beds; means for reciprocating said cylinders; web feeding and delivering mechanism; means for directing the web from the feeding mechanism successively between the cylinders and beds to be printed; means for stopping the forward movement of the portion of the web being printed just prior to and during the printing operation; and means for shifting forward the printed portions of the web while the cylinders are 55 clear of the forms with means to tension the portion of the web intermediate the beds during the printing operation and to slack this portion of the web after the printing operation.

8. In a printing press as set forth in claim

6, means for tensioning the portion of the web between the feed and delivery just before and during the printing operation and for slackening the intermediate portion of the web after the printing operation and while such portion of the web is being shifted forward.

9. In a flat bed press as set forth in claim 6; a looping roller traveling with the cylinders; rocking levers carrying said roller, and cam means adapted to move the roller so as to tension the intermediate portion of the web during the printing operation, and slack this portion of the web after the printing operation.

10. In a flat bed web printing press the combination of two type beds, a pair of cylinders operating on one bed; a pair of cylinders operating on the other bed; cross heads in which said cylinders are journaled; means for reciprocating the cross heads to move the cylinders back and forth over the beds so that two impressions are made by each pair of cylinders from the forms on the related bed at each stroke of the cylinders; a web feeding mechanism; a web delivery mechanism; means for directing web from the feeding mechanism successively between one bed and its pair of related cylinders and then between the other bed and its pair of related cylinders and then to the delivery, means for looping the web between the cylinders in each pair so that the two impressions produced by such cylinders from the form on the related bed will be on different portions of the same web; devices for looping the web between the feeding mechanism and the first cylinder, and between the delivery mechanism and the last cylinder, whereby the intermediate portion of the web is stopped during the taking of impressions and then shifted forward between the beds and cylinders after the taking of impressions; and means co-acting with the looping devices whereby a length of web equal to two impressions plus margins is shifted between the feeding and delivering mechanisms while the cylinders are clear of the forms at each end of the beds.

11. In a printing press as set forth in claim 10, means for tensioning the portion of the web between the feed and delivery just before and during the printing operation, and means for slackening such portion of the web after the printing operation and while such portion of the web is being shifted forward.

12. In a printing press as set forth in claim 10, said web looping mechanism comprising an oscillating lever carrying looping rollers on its upper and lower ends, a cam geared directly to the crank gears and a bell crank lever having one arm engaging said cam and a link connecting the other arm of said crank lever to said looping lever,

to oscillate the latter, substantially as described.

13. In a printing press as set forth in claim 10, a web guide roller between the 5 impression cylinders in one pair over which the web is looped, and means for shifting said roller so as to slack the intermediate portion of the web after the printing operation and while such portion of the web is being shifted and return said roller to normal 10 position to properly tension the intermediate portion of the web prior to and during the printing operation.

14. In a printing press as set forth in claim 10, a looping roller traveling with the cylinders, rocking levers carrying said roller, a cam adapted to cause the levers to move the roller so as to tension the intermediate portion of the web during the printing 20 operation and permit the roller to move and slack this portion of the web after the printing operation.

15. In a flat bed web printing press the combination of two type beds arranged in 25 parallel planes; a pair of cylinders operating on one bed; a pair of cylinders operating on the other bed; cross heads in which said cylinders are journaled; crank gears and pitmans for reciprocating these cross 30 heads to move the cylinders back and forth over the beds; a continuously operating web feeding mechanism; a continuously operating web looping mechanism; means for directing a web from the feeding mechanism 35 successively between the pair of cylinders and related beds to the delivery; means for looping the web between the cylinders in each pair so that the two impressions produced by such cylinders from the form 40 on the related bed will be on different portions of the web, and two impressions be made by each pair of cylinders from the forms on the related bed at each stroke of the cylinders; means for looping the web 45 between feeding mechanism and the first cylinder and between the delivering mechanism and the last cylinder and whereby the intermediate portion of the web is stopped during the taking of impressions 50 and then shifted forward between the beds and cylinders after taking the impression; said mechanism operating to shift a length of web equal to two impressions plus margins between the feeding and delivering mechanism while the cylinders are clear of the forms at each end of the beds.

16. In a printing press as set forth in claim 15, means for tensioning the portion of the web between the feed and delivery just before and during the printing 60 operation, and means for slackening such portion of the web after the printing operation and while such portion of the web is being shifted forward.

17. In a web printing press as set forth

in claim 15, the web looping mechanism comprising an oscillating lever carrying looping rollers on its upper and lower ends, a cam geared directly to the crank gears and a bell crank lever having one arm engaging said cam and a link connecting the other arm of said crank lever to said looping lever to oscillate the latter, substantially as described.

18. In a printing press set forth in claim 15, a web guide roller traveling with the impression cylinders over which the web is looped and means for shifting said roller so as to slack the intermediate portion of the web after the printing operation and while such portion of the web is being shifted and return said roller to normal position to properly tension the intermediate portion of the web prior to and during the printing operation.

19. In a printing press as set forth in claim 15, a looping roller intermediate the cylinders in one pair, rocking levers carrying said roller, a cam adapted to cause the levers to move the roller so as to tension the intermediate portion of the web during the printing operation and permit the roller to move and slack this portion of the web after the printing operation.

20. In a flat bed printing press the combination of a bed and a reciprocating cylinder cooperating with the bed, a crank gear and connections for operating the cylinder, a web feeding roll, a web delivery roll, and direct gearing between the feed roll and 100 said crank gear, and a gear on the delivery roll meshing with said crank gear.

21. In a web printing press the combination of a pair of beds, a pair of cylinders co-acting with the beds, a web feeding roll, 105 a web delivery roll, means for guiding the web from the feeding roll to the delivery roll, crank gears and connections for reciprocating the cylinders, a gear on the feeding roll directly meshing with the crank 110 gear, and a gear on the delivery roll directly meshing with the crank gear.

22. In a web printing press, the combination of a pair of beds, a pair of cylinders co-acting with the beds, a web feeding roll, 115 a web delivery roll, means for guiding the webs from the feeding devices to the delivery devices, web looping devices, and a cam for operating said devices; with crank gears and connections for reciprocating the 120 cylinders; a gear on the web feeding roll directly meshing with the crank gear; a gear on the delivery roll directly meshing with the crank gear, and direct gearing between the crank gear shaft and the cam for 125 operating the looping rollers.

In testimony that I claim the foregoing as my own, I affix my signature.

PAUL F. COX.
